UNITED STATES PATENT OFFICE

2,351,506

DISPENSING MECHANISM

Henry F. Hagemeyer, Chicago, Ill., assignor to
Castings Patent Corporation, Chicago, Ill., a
corporation of Illinois

Original application July 11, 1939, Serial No.
283,868. Divided and this application March
11, 1941, Serial No. 382,707

5 Claims. (Cl. 83—93)

My invention relates to material dispensing mechanism of a type adapted to mix powdered material with a liquid and dispensing measured quantities of the resulting fluid mixture, and more particularly, to means for comminuting the powdered material.

For a more complete explanation of my process and the construction and operation of a machine capable of performing such process, and of which the dispensing mechanism disclosed and claimed herein forms a part, reference may be had to my Patent No. 2,291,710 (granted August 4, 1942, upon an application filed February 24, 1941) which is a division of my co-pending application Serial No. 283,868, filed July 11, 1939, entitled Improvements in dispensing machines and process, of which this application also constitutes a division. For this reason, it is not believed necessary to set out herein a detailed description of the process and the construction and operation of a machine capable of performing such process, except that a description of the dispensing mechanism will be made in so far as is necessary to adequately describe the operation of the comminuting means which forms the basis of the present application.

In general, the process and the operation of the dispensing machine, capable of carrying out this process, comprises means for delivering a predetermined quantity of powdered material in a downwardly falling sheet. During the descent of the powdered material it passes through comminuting means provided to insure the removal from the downwardly falling sheet of the clotting characteristics which such sheet may possess, without substantial disturbance to the form or shape of the downwardly falling sheet. The downwardly falling sheet is subsequently commingled in a liquid medium and the resulting mixture is then dispensed in measured quantities into a receptacle or container.

The comminuting means hereinbefore mentioned has been found essential in order to insure the proper operation of the dispensing mechanism when the dispensing mechanism is employed in the process of preparing gypsum base molds, however there are other uses to which the dispensing mechanism may be employed, in which the clotting characteristics of the downwardly falling sheet would not impair the success of the dispensing mechanism, and in which the comminuting means may be eliminated.

In the forming of gypsum base molds it is essential that the powdered material, which is employed in forming the mold or mold part, be

5 free from lumps or clotting. If clotting occurs, portions of the mold will be irregular and the porosity of the cured mold would be impaired. In order to overcome this difficulty, there has been provided in the dispensing mechanism of my invention, a comminuting means which insures the elimination of the clotting characteristics in the powdered material, and operates to fluff the material before it is commingled with the liquid medium.

10 The comminuting means of the present invention may, for example, include transverse wires which will cut through the falling material sheet at relatively high speed to break up any lumps or clots therein by the force of the impact of the lumps or clots against the transverse wires. It is preferred that the wires pass through the falling material sheet in a downwardly direction, deriving their striking ability from a downward 15 movement faster than the falling speed of the powdered material. Such operation, as heretofore mentioned, will have no appreciable effect upon the uniformity of the stream's size and shape, the general course of falling being undisturbed.

20 An object of the present invention is to provide means to insure the powdered material will be free from clots and lumps at the time it comes into contact with the liquid medium, even though such material may have a tendency to cake or pack.

25 A further object of the present invention is to provide a comminuting means positioned in the path of a sheet of material which is required to pass through the said means before being commingled in a liquid medium.

30 Other objects and advantages of my invention will become more apparent from the following description, reference being had to the accompanying drawing, in which:

35 Fig. 1 is an enlarged view, partly in vertical section and partly in side elevation, of the comminuting and spray means of my mechanism, and

40 Fig. 2 is a vertical section taken on line 2—2 of Fig. 1.

45 Referring now to the drawing, and more specifically to Fig. 1, 1 indicates a portion of a storage bin into which the material to be dispensed is delivered. The storage bin 1 may be made of any desired construction, such as open at the top to permit manual filling of the bin, or so constructed as to permit automatic filling of the bin by permitting a conveyor means to pass into and out of the bin or conveyor means to pass

over the open top bin to deposit the material in the bin.

In the lower portion of the storage bin 1, there is provided a measuring belt 2. The measuring belt is composed of equally spaced cross bars or slats 20, having their opposite ends secured to spaced chains 21. These chains are carried by an idler drum (not shown) mounted in the upper portion of the storage bin 1 and a driven drum 23 mounted just above the discharge outlet 18 in the bottom of bin 1. Suitable mechanism will be provided to drive the drum 23 at a speed sufficient to move the slats 20 rapidly through the body of the powdered material to keep it in a state of live suspension, so that it will be of uniform and constant density throughout the zone of movement of belt 2. As shown in Fig. 2, drum 23 extends from side to side of the bin 1, to seal the powdered container portion thereof from the discharge outlet except for the narrow curved passage around its periphery through which belt 2 moves.

Not only does the belt act as an agitator for the stored material, but the equally spaced bars 20 constitute measuring chambers therebetween of equal size. These measuring chambers are filled with constant density powdered material as the belt 2 passes through the upper portion of the storage bin 2, and as the slats move down closely adjacent to the bin wall 3, as shown in Fig. 1, the measuring spaces are completely closed between the drum 23 and the wall 3. In this way successive increments, portions or parcels of powdered material of equal volume are moved from the main body of the material in the storage bin to the discharge outlet 18. Because of the bending of the belt beneath the drum 23, the outer edges of the adjacent slats are spread slightly apart to free the powdered material dropped therebetween. It will be evident that since the material is kept in uniform density suspension and is moved to the outlet in increments of equal volume, a definite known weight of powdered material, directly proportional to the number of increments, may readily be delivered. Depending upon the time involved during which it is desired to have such a known quantity of material dispensed, the speed of belt 2 may be established for bars of a certain width and spaced a certain distance apart. In order to weigh batches of material within slight differences, the measuring chambers should be quite small. The speed of the measuring belt may be regulated to change the rate of material delivered, and an automatic mechanism may be provided to start and stop the belt as required to dispense batches of any weight.

To prevent powdered material packing between drums 23 and the measuring belt 2, thus causing the slats 20 to scrape heavily against the wall 1, an enabling additional powdered material to be packed into the measuring spaces, scrapers 24 are provided in the entering angle between the drum and belt to scrape all powdered material from the drum periphery.

Below the opening 18 of bin 1, there is positioned comminuting or fluffing means which is employed to break up the lumps or clots in the powdered material dropped in the freely falling sheet through the opening 18. The comminuting means is housed in a casing 3 attached to the bottom of storage bin 1 and covering the discharge outlet. At each side of the casing 3, preferably in a recess (see Fig. 2) is mounted a pair of sprockets 30. Striking elements such as wires

31, which can be stretched under tension, extend between and are secured to corresponding sprockets of the opposite pairs. These striking wires 31 are driven through the falling sheet of powdered material to strike against the particles thereof. While the wires may move generally upward or downward, or even transversely of the material sheet, I prefer that the sprockets turn in the direction of the arrows in Fig. 1, so that the wires may move through the powdered material generally in its direction of fall. The speed of the wires in order to strike the material sharply in such case must be considerably in excess of the falling speed of the powdered material, but the sheet will not be appreciably dispersed by the fluffing operation if the wires pass through it in this manner. On the contrary, where the sheet is composed of a progression of falling increments, it will leave this fluffing mechanism in almost a continuously uniform sheet. Air pipes 32, delivering air under small pressure, may be provided to slightly increase the falling speed of the powdered material over that which it would acquire from gravity, and to prevent powdered material dust collecting upon or blowing up in the casing 3 after it emerges into the air.

From the casing 3 the fluffed powdered material will drop in a falling sheet through spout 33. Spray nozzles 4 will be arranged adjacent to the casing 3, for dispensing a spray of liquid against the powdered material sheet to mix therewith. The number and arrangement of the nozzles may be varied within wide limits, as explained fully in my heretofore referred to co-pending application Serial No. 380,325, filed February 24, 1941, which matured into Patent No. 2,291,710. Preferably the nozzles 4 are adjustable for positioning in any one of various positions and attitudes (see Fig. 1). They are carried by a conduit having a swivel joint 40 rotatable to adjust the angle of the nozzles to the falling powdered material sheet.

It will thus be seen that I have provided means for fluffing the powdered material which is delivered to and dropped through an opening in a bin and which must pass through a comminuting means before being ejected through an outlet into a fluid medium to be subsequently dispensed as a mixture of water and powdered material into a container. The fluffing mechanism or comminuting means will eliminate all clotting characteristics of the falling sheet and eliminate the possibility, when the device is used in the process of making gypsum base molds, of deformities from being present in the molds.

Having thus described my invention, what I claim as new and desire to secure by Letters Patent of the United States is:

1. Dispensing mechanism, comprising means for delivering measured quantities of powdered material in a freely falling sheet, fluffer mechanism including two opposite pairs of intermeshing sprockets, and a plurality of wires, constituting striking elements, stretched between, said pairs of sprockets, and means to rotate said sprockets, one of said pairs of sprockets being adapted to rotate in a clockwise direction and the other of said pairs of sprockets being adapted to rotate in a counterclockwise direction thereby to drive said wires through the sheet of freely falling powdered material for impacting the particles thereof, to break up any clots in such material and to fluff it, said fluffer mechanism being adapted to receive and expel said sheet without altering its direction of fall.

2. Means for dispensing measured quantities of powdered material in a thin elongated freely falling sheet, said means including means for fluffing said sheet, said fluffing means comprising a pair of positively rotatable overlapping elongated members positioned adjacent one another and directly in the path of said sheet of falling material, each of said members having a plurality of wires extending between the end portions thereof, each of said pair of rotatable members being adapted to be rotated at a speed greater than the speed of fall of said powdered material, whereby said sheet of freely falling material is received and expelled from said rotatable members without materially altering the direction of fall of said sheet or its general form.

3. A dispensing mechanism for removing clots from and fluffing a freely falling stream of powdered material, including a pair of rotatable structures each including a plurality of axially extending spaced apart wires, said structures being rotatable to move the wires of each structure through a portion of the path of the stream and certain of said wires intermeshing in the path, and means for rotating said structures so that the wires move in the general direction of the stream when in the path of the stream and at a speed in excess of the fall of material thereby to fluff and break up any clots in the material without materially dispersing it.

4. A dispensing mechanism for removing clots from and fluffing a freely falling stream of powdered material, including a pair of rotatable structures arranged on opposite sides of the stream, each including a plurality of axially ex-

tending spaced apart wires, said structures being closely spaced and constructed so that when rotated the wires of the two structures act upon the entire stream, and means for rotating said structures in opposite directions so that the wires move in the general direction of the stream when in the path of the stream and at a speed in excess of the fall of the material thereby to fluff and break up any clots in the material without materially dispersing it.

5. A dispensing mechanism for removing clots from and fluffing a freely falling stream of powdered material, including a pair of rotatable structures each having a pair of spaced end members and the structures mounted on parallel axes and each structure including a plurality of axially extending spaced apart striking elements, each striking element being secured at its opposite ends in fixed relation to said end members, said structures being closely spaced and constructed so that when rotated the striking elements of the two structures act upon substantially the entire stream, and said striking elements consisting of members each having a small cross-section area and having a small area in the direction of its movement and also in the direction of fall of said material, and means for rotating said structures in opposite directions so that the striking elements move in the general direction of the stream when in the path of the stream and at a speed in excess of the fall of the material thereby to fluff and break up any clots in the material without materially dispersing it.

HENRY F. HAGEMEYER.
